UNITED STATES PATENT OFFICE.

MILES W. O'BRIEN, OF OTTAWA, ILLINOIS.

SHOE-TREE.

SPECIFICATION forming part of Letters Patent No. 752,409, dated February 16, 1904.

Application filed December 20, 1902. Serial No. 135,973. (No model.)

To all whom it may concern:

Be it known that I, MILES W. O'BRIEN, a citizen of the United States, residing at Ottawa, county of Lasalle, and State of Illinois, have invented certain new and useful Improvements in Shoe-Trees, of which I do declare the following to be a full, clear, and exact description, reference being had to the accompanying drawings, forming part of this specification.

The present invention has for its object to provide a simple, durable, cheap, and effective construction of shoe-tree, whereby the wrinkling of the leather of shoes will be prevented and the natural shape of the shoe will be maintained.

The invention consists in the features of novelty hereinafter described, illustrated in the accompanying drawings, and particularly defined in the claims at the end of this specification.

Figure 1 is a view in side elevation of the shoe-tree embodying my invention. Fig. 2 is a view in central vertical longitudinal section through the tree with the parts in position for use. Fig. 3 is an inverted plan view showing the parts in folded position. Fig. 4 is a view in cross-section on line 4-4 of Fig. 3.

In the preferred form of the invention the toe portion A of my improved shoe-tree is formed from sheet metal, the lower edges of the metal being turned inwardly, as at a. By this construction a toe portion of the desired strength is obtained, and this portion being hollow permits a free circulation of air to all parts of the shoe, thus prolonging the life of the leather. The flange a around the edge of the toe portion A serves to give great strength to such part, and thus preserve its shape, while permitting it to be made very light. To the under side of the toe portion A at its rear is pivotally connected a link or lever B, the outer end of which link or lever carries a swivel-nut C, through which passes an adjusting-screw D, having a heel-form E, preferably of semiglobular shape. As shown, the forward end of the link or lever B is pivotally connected by a pin a' to the arms of the bracket a'', that is riveted to the under side of the toe portion A, and preferably the end of the link or

lever B has upwardly-turned arms b, through which the pivot-pin a' passes. As shown also, the opposite or rear end of the link or lever B has upturned arms b'', through which passes a pin b', that passes through the swivel-nut C. 55 As shown, the link or lever B is of concavo-convex form, as by this means the link or lever is greatly strengthened without increasing its weight.

The heel-form E is formed with a central hole to receive the reduced end of the screw D, and preferably that portion of the heel-form E adjacent the central hole is depressed or countersunk, as shown at e, so that the end of the screw will not contact with the heel of the shoe. The heel-form E is held in position upon the shoulder d of the screw, while the upset or riveted reduced end d' of the screw retains the heel-form against displacement, while permitting the screw to revolve freely with respect to the heel-form E. The free end of the screw D is furnished with a thumb-nut or wheel D', whereby the screw may be turned in order to effect the desired adjustment of the parts. 75

By reference more particularly to Fig. 1 of the drawings it will be seen that in using my improved shoe-tree the toe portion A will be inserted beneath the vamp of the shoe with the link B and the screw D extending upwardly from the horizontal, while the heel-form E rests against the heel portion of the shoe. By depressing the screw and link from the position shown in Fig. 1 to the position shown in Fig. 2 the toe portion A is thrust outwardly into the toe of the shoe, as shown in Fig. 2, the thrust being then in the line of the link and screw and serving to retain these parts in position. By adjusting the screw D, which may be done after the tree is in the shoe, as shown, the snug fitting of the toe portion of the tree into the corresponding part of the shoe may be secured, the leather being stretched, so as to remove wrinkles therefrom and maintain the natural shape of the shoe. It will be observed that the link B and the screw D form a simple adjustable toggle intermediate and connecting the heel and toe portions of the tree, so that the latter may be easily and quickly forced apart with considerable pres- 100

sure to snugly fit within the shoe by simply pushing the members of the toggle into line with each other and also so that the tree may be quickly removed from the shoe by simply 5 breaking the toggle-joint.

By reference more particularly to Fig. 3 of the drawings it will be seen that when the parts are to be packed for transportation the link or lever B, and with it the adjusting-screw D, will be folded into the hollow portion 10 of the toe portion A, so as to occupy very little space. One marked advantage of my improved shoe-tree is that although it is of great strength and will stand severe usage 15 still it is exceedingly light and can be folded into most compact form for shipment. It will be seen that as inasmuch as the forward end of the adjusting-screw D extends in front of the swivel-nut C when the link B is turned to 20 approximately horizontal position, as shown in Fig. 2, the bearing of the thumb-nut D' against the link will limit the extent of downward movement of the link, and thus serve to hold it practically upon the dead-center.

25 It is manifest that the precise details of construction above set out may be varied without departure from the spirit of the invention, and features of the invention may be employed without its adoption as an entirety.

30 Having thus described my invention, what I claim is new, and desire to secure by Letters Patent, is—

35 1. A shoe-tree consisting of a toe portion, a heel-block and an intermediate adjustable toggle connected thereto for spreading said parts comprising a link forming one member of said toggle, a nut swiveled to said link and a screw forming the other member of said toggle threaded through said nut.

40 2. A shoe-tree consisting of a toe portion, a heel-block and an intermediate adjustable toggle connected thereto for spreading said parts comprising a link forming one member of said toggle and an adjusting-screw and nut therefor 45 forming the other member of said toggle pivotally connected to said link, one of said toggle members having an extended end portion adapted to engage the other and thereby limit the extent of depression of said members.

50 3. A shoe-tree consisting of a toe portion, a

heel-block and an intermediate adjustable toggle connected thereto for spreading said parts comprising a link forming one member of the toggle and an adjusting-screw and nut therefor forming the other member thereof and 55 having a single pivotal point of connection with said link, said toggle members being adapted to be extended substantially in line and hold the toe portion and heel-block snugly in position within the shoe.

60 4. A shoe-tree comprising a toe portion, a link pivoted thereto at one end and provided at its opposite end with a swivel-nut and an adjusting-screw passing through said swivel-nut and provided with a heel form or part 65 adapted to bear against the heel of the shoe.

5. A shoe-tree comprising a toe portion formed of a curved metal plate, a link pivoted to the under side of said plate and provided at its opposite end with a swivel-nut, an adjusting-screw passing through said swivel-nut and provided at one end with a heel-form and at its opposite end with a thumb-nut or wheel 70 whereby the screw may be turned.

6. A shoe-tree comprising a toe portion, a link pivoted thereto and extending rearwardly therefrom, an adjusting-screw pivotally connected with the rear end of said link and having a part extending forwardly of its pivotal connection with said link, said part being 75 adapted to limit the movement of the link after it has passed below a horizontal line, and a heel-form swiveled to the rear end of said screw whereby when the parts are in position for use the forward end of said screw will 80 limit the depression of the link and whereby the screw may be turned without revolving the heel-form.

7. In a shoe-tree, the combination with a toe portion, of a link pivotally connected to 90 said toe portion, said link being formed of a transversely-curved metal plate, an adjusting-screw provided with a swivel-nut that is pivotally connected to said link and a heel-form connected to the outer end of said adjusting-screw.

MILES W. O'BRIEN.
